CABINET DOOR CONSTRUCTION

Mortimer A. Gersten, New York, N. Y.

Application July 24, 1948, Serial No. 40,489

2 Claims. (Cl. 312—329)

1

The present invention relates to cabinets and the like, used for the storage of clothing, linens etc., and more particularly to the type made of wood-trimmed paper board, fibre board and similar materials, various embodiments of which are manufactured knockdown; but easy to assemble. The cabinets herein concerned with, are of the kind which have one or more swingable doors.

These cabinets are made without the precision of fit as is mandatory in fine furniture, because they are of necessity a reasonably cheap structure where even if a single wood slat could be omitted, it would be of great advantage because of the small profit margin these goods must be sold at. Further it is desirable that the doors when closed, shall as far as is possible, keep moths and dust from entering the cabinet. Heretofore, in manufactures of this type, fairly good closure was obtained at the top, bottom and handle edges of the doors, but an objectionable open slit remained usually along the hinge edge of each door. Of course, better fit and avoidance of such slits could be attained by recessing the seats for the hinges and use of skill in door mounting. Such practice here would be prohibitive because of the cost factor.

It is therefore an object of this invention to provide a novel and improved construction which eliminates said open slit condition at the hinge line of the closed door.

Another object hereof is to provide a novel and improved construction of the character mentioned which eliminates said open slit condition and dispenses with certain of the door wood trim, thereby effecting a saving in the cost of manufacture.

A further object hereof is to provide a novel and improved construction of the nature set forth, which is easy to make, which maintains the sturdiness of the door paper board panel using a minimum of wood trim, and which is efficient in carrying out the purposes for which it is designed.

Other objects and advantages will become apparent as this disclosure proceeds.

In the accompanying drawings forming part of this specification, similar characters of reference indicate corresponding parts in all the views.

Fig. 1 is a perspective view of a cabinet embodying the teachings of this invention.

Fig. 2 is a section taken at lines 2—2 in Fig. 1, showing the relation of parts when the door is open.

Fig. 3 is a similar view showing the door closed. 55

2

Fig. 4 is a similar view showing the old practice.

In the drawings, the numeral 15 designates a cabinet, which essentially is a box structure having a paper-board body 16, trimmed with wood slats around its top and body, as at 17 and 18, or some similar structure in other manner wood-trimmed as is well known in the art. The body has a wood stile 19 mounted on its front, to carry the hinges 20 for a door 21 of paper-board panel with a vertical wood slat 22 mounted along its handle-edge. It is to be noted that the hinge-edge of the door is free of wood trim.

In stile 19, along its side which is nearest the hinge-edge of the door 21, is a flared longitudinal groove 23, in which the door panel at hinge-edge resides when said door is closed, and preferably is "pinched" at 24, and in good surface contact at 25, even if said door panel is caused to bend slightly in region "A" to accomplish this. Said door panel 21, being somewhat resilient, makes such bending possible. The hinge leaf 20 secured on the door, is suitably bent in form so that the door panel be positioned as shown. The groove 23, is so positioned and dimensioned that it permits door opening and closing. The hinge line is of course inward of hinge-edge and slightly towards handle-edge of the door. If desired, the stile 19 may be made without portion "B," in which instance when the door is closed, the door panel will contact only surface 25. In either construction of stile, when the door is closed, no dust or moths could enter at the hinge-edge of the door, as was possible in the old construction 35 as illustrated in Fig. 4, where the numeral 27 denotes the open slit existing between the stile 28 fixed on cabinet body 29 and the slat 30 along the hinge-edge of the door panel. The numeral 32 indicates the hinge.

40 The necessity of a wood slat mounted along the hinge-edge of the door panel has been eliminated, for it is to be noted that when the door is closed, the engagement thereof within groove 23 of stile 19, acts to maintain the door firm and rigid therealong, just as if said stile were a slat secured along the hinge-edge of said door panel. In fact, when the door is closed, such is the appearance.

45 Thus, as set forth, I have provided a cabinet which gives greater safety against moths and dust than was heretofore attained in this type of manufacture and have decreased the cost of production without change in appearance.

This invention is capable of numerous forms and various applications without departing from

the essential features herein disclosed. It is therefore intended and desired that the embodiments herein be deemed illustrative and not restrictive and that the patent shall cover all patentable novelty herein set forth; reference being had to the following claims rather than to the specific description herein to indicate the scope of this invention.

I claim:

1. In an article of the character described, a door of material of the paper-board type and a stile; said door being hingedly mounted on the stile about an axis along and a little inward of an edge of the door; the stile presenting a longitudinal surface behind its front surface; the hinge axis being at a slightly lesser distance from the front surface of the door than from the mentioned longitudinal surface on the stile; the front surface of the door along its said edge, being positioned in contact with said longitudinal surface of the stile when the door is closed and when the door is being closed, the front surface thereof along the mentioned edge contacts said longitudinal surface of the stile and is flexed thereby along a longitudinal line upon being fully closed.

2. In an article of the character described, a door of material of the paper-board type and a stile; said door being hingedly mounted on the

stile about an axis along and a little inward from an edge of the door; said stile being provided with a groove along its side edge adjacent the hinged-edge of the door; the hinge axis being at a slightly lesser distance from the front surface of the door than from the wall of the groove which is nearest the front surface of the stile; the door, along its said hinged-edge being positioned within said groove when the door is closed and withdraws from said groove when the door is opened, and when the door is being closed, its hinged-edge front surface contacts the wall of the groove nearest the front surface of the stile and is flexed thereby along a longitudinal line upon being fully closed, and when fully closed, said door at its hinged-edge is in contact with the opposite longitudinal walls of said groove.
